US00D651167S

(12) **United States Design Patent**
Lemelman et al.

(10) **Patent No.:** US D651,167 S
(45) **Date of Patent:** ** Dec. 27, 2011

(54) **POWER MODULE FOR PORTABLE ELECTRONIC DEVICES**

(75) Inventors: **Brian Lemelman**, Juno Beach, FL (US); **Alexandra Lemelman**, New York, NY (US); **David Lemelman**, New York, NY (US); **Paul Koh**, New York, NY (US); **David Northway**, Sunnyvale, CA (US); **Victoria Slaker**, San Francisco, CA (US); **Gregoire Vandenbussche**, San Francisco, CA (US); **William Franklin Dunn, Jr.**, Austin, TX (US)

(73) Assignee: **Third Rail Mobility, LLC.**, Juno Beach, FL (US)

(**) Term: **14 Years**

(21) Appl. No.: **29/386,092**

(22) Filed: **Feb. 24, 2011**

(51) **LOC (9) Cl.** 13-02

(52) **U.S. Cl.** **D13/103**

(58) **Field of Classification Search** D13/102–106, D13/110, 118–119, 184, 199; 429/96–100, 429/163, 176

(57) **CLAIM**

The ornamental design for a power module for portable electronic devices, as shown and described.

DESCRIPTION

FIG. 1 is a perspective view of a power module for portable electronic devices showing our new design;

FIG. 2 is a second perspective view thereof;

FIG. 3 is a front view thereof;

FIG. 4 is a back view thereof;

FIG. 5 is a left view, the right view being a mirror image thereof;

FIG. 6 is a top view thereof; and,

FIG. 7 is a bottom view thereof.

The broken lines in the figures are included for the purpose of illustrating the environment and form no part of the claimed design.
